UNITED STATES PATENT OFFICE.

RODNEY W. MANNING, OF RIVERSIDE, RHODE ISLAND.

VALVE OR TAPPET ADJUSTING DEVICE.

1,294,134.

Specification of Letters Patent. Patented Feb. 11, 1919.

Application filed October 3, 1917. Serial No. 194,509.

To all whom it may concern:

Be it known that I, RODNEY W. MANNING, a citizen of the United States, residing at Riverside, in the county of Providence and

5 State of Rhode Island, have invented a new and useful Improvement in Valve or Tappet Adjusting Devices, of which the following is a specification.

This invention relates to certain new and 10 useful improvements in a valve or tappet adjusting device, and it has for its primary object to provide a device attachable either to the lower end of the valve stem or the top of the tappet for effecting a closer relation 15 between the tappet and valve to eliminate "pounding" in the engine.

The invention consists broadly in a holder 20 that is adjustably mounted on the lower end of a valve stem or the upper end of a tappet, which holder is provided with a bottom wall constituting a bearing surface, a wedge interposed between the bottom wall of the holder and the holder carrying element, and means for urging the wedge inwardly across 25 the bottom wall to always maintain a close relation between the latter and the element which is not supporting the holder.

The invention further consists in the features of construction and the arrangements 30 and combinations of parts hereinafter specifically described and succinctly claimed, reference being had to the accompanying drawing wherein—

Figure 1 is a side elevation of the improved device applied to the lower end of a 35 valve stem.

Fig. 2 is a horizontal section on line 2—2 of Fig. 1, showing the adjusting device in plan.

40 Fig. 3 is a vertical section therethrough.

Fig. 4 is an end elevation of the device in its operative position, and

Fig. 5 is a bottom plan thereof.

Referring more in detail to the accompanying drawing, the numeral 1 designates either the lower end of a valve stem or a tappet, the latter of which may be of that type disclosed in the patents to R. W. Manning, numbered 1,193,913 and 1,212,980.

45 The adjusting device, which may be mounted and carried either on the lower end or upper end, depending upon the type of valve or tappet, comprises a holder 2, a wedge member 3 slidably supported there-

55 by, and a coiled spring 4 for subjecting the

slide of wedge to pressure for urging the latter longitudinally on its support.

The holder is preferably formed of sheet metal bent into U form and disposed horizontally about the lower end of the stem 1, 60 a bolt 5 passing through the arms 6 and cooperating with a nut 7 to contract or release said arms, the metal from which the holder is formed possessing sufficient resiliency for such purpose. The lower edges of the 65 holder are inturned to provide ledges 8 which constitute a bottom wall that extends across the lower end of the valve stem and is preferably beveled or inclined, as depicted in Fig. 3.

70 The wedge member is supported by the bottom wall 8 for sliding across the lower end of the stem 1, the side walls or arms serving as guide means for the wedge. The forward or attenuated end of the wedge projects through a slot 9, provided at the rear of the holder and defined at its lower edge by the bottom wall 8 and the rear end of said wedge is formed with a seat 10 which engages one end or terminal of the coiled 80 spring 4.

75 The coiled spring encircles the screw bolt 5 and has its opposite end hooked over the adjacent side wall of the holder. Consequently, when the nut 7 is loosened the 85 spring will be free to force the wedge member across the bottom wall and project it farther through the slot 9. Such movement of the wedge will, therefore, cause the bottom wall to be further spaced from the 90 end face of the valve stem or in other words effect a sliding of the holder along the stem in a downward direction.

To guide the holder during such sliding action and to also lock the holder against 95 free rotative movement, the upper edge of the holder is provided with a pair of diametrical slots 11 adapted to receive the pin 12 which is employed to hold the valve seating spring on the stem, said spring being 100 omitted in the present showing. The forward slot 11 is defined by the opposing ends of a pair of fingers 13 bent inwardly from the side arms or walls of the holder, thus giving the upper portion of the latter a circular cross section, as illustrated in Fig. 2.

In operation, the holder is mounted either on the tappet engaging end of the valve stem or the stem-engaged part of the tappet, as shown, with the wedge member initially 110

disposed in a retracted position, as depicted in Fig. 1, and bearing against the stem end. As wear takes place between the stem and tappet, or, as in the present instance, between the bottom wall 8 and the tappet, the nut 7 is unscrewed to permit the spring sliding the wedge inwardly across the bottom wall and effect down movement of the holder to take up the space between the tappet and valve stem. The action of the spring on the wedge may be made entirely automatic by leaving the nut loosened so that the sides of the holder do not bear or bind on the wedge, if such action is desired. It will therefore be noted that the wear is automatically or otherwise taken up as it occurs and that any possibility of pounding will be entirely eliminated. The terms "valve stem" or "stem" are used in their broadest sense in the foregoing description and the following claims to include also the tappet when the model or construction of the engine is such as to prevent the mounting of the device on the valve stem.

Having thus described my invention, what I claim as new and desire to secure by Letters Patent is:—

1. In combination with a valve stem, a holder adjustably carried by the tappet engaging end of the stem and comprising a sheet metal body bent into U-form and horizontally disposed in straddling relation to the stem, means connecting the arms of the U-holder for creating a frictional grip on the stem, a wedge member slidably supported across the specified end of the stem in contact therewith, and a spring for urging the wedge across the end of the valve stem.

2. In an adjusting device, a holder of U-form adapted to embrace the tappet engaging end of a valve stem, the lower edges of the holder being inturned across the stem end, a wedge member slidably supported by the inturned edges against the specified end of the valve stem, and means for moving the wedge across the latter.

3. An adjusting device comprising a holder having its lower edges inturned, a wedge member slidably supported by the inturned edges, and a coiled spring carried by the holder and having one terminal portion bearing against the adjacent end of the wedge to move the latter in its mounting.

4. An adjusting device comprising a holder slidably supported on a valve stem and formed with vertical slots for receiving the spring supporting pin of said stem, the lower edges of the holder being inturned across the end of the stem, the faces of the inturned edges that oppose the stem end being inclined transversely thereof, and a spring pressed wedging member slidably supported by the inturned edges of the holder.

5. An adjusting device comprising a holder of U-form adapted to embrace the lower end of a valve stem, the upper edge of the holder being provided with vertical slots adapted to receive the spring holding pin of the stem for guidance, and the lower edge of the holder being inturned from opposite sides, the upper faces of the inturned edges being beveled, a wedge member slidably supported on the inturned edges, a screw bolt connecting the arms of the U-holder, and a coiled spring encircling the bolt and having one terminal bearing against the wedge member to urge it across the inturned edges.

6. An adjusting device comprising a holder adapted to be mounted on the tappet-engaging end of a valve stem and provided with a bottom wall opposing the end of the stem, and a wedge member slidably supported by the bottom wall for movement between the latter and the end of a valve stem.

In testimony whereof I have signed my name to this specification in the presence of two subscribing witnesses,

RODNEY W. MANNING.
